UNITED STATES PATENT OFFICE.

REUBEN D. COY, OF GLENCOE, ILLINOIS.

ROTARY WEB-PRINTING MACHINE.

No. 863,591.

Specification of Letters Patent.

Patented Aug. 20, 1907.

Application filed September 4, 1906. Serial No. 333,149.

To all whom it may concern:

Be it known that I, REUBEN D. COY, a citizen of the United States, residing at Glencoe, in the county of Cook and State of Illinois, have invented certain new and useful Improvements in Rotary Web-Printing Machines, of which the following is a specification.

This invention relates to improvements in printing machines of that class wherein a continuous web is drawn from a roll and printed upon by rotating curved printing-surfaces and severed into sheets of desired lengths.

In the printing of work in which more than one impression is to be made upon the sheet at the same point, either in different colors upon the same side, or in the same color or different colors upon the opposite sides of the sheet, it is of great importance that successive impressions register accurately. Heretofore it has been found to be difficult to do this class of work upon rotary web-printing machines, for the reason that in such machines, as heretofore constructed and operated, the web moves continuously and it is a matter of great difficulty to attain accurate register of a plurality of impressions upon a moving web.

The object of my invention is the production of a machine which is capable of placing a plurality of impressions upon the web at the same point in the length of the same with the desired accuracy. In the accomplishment of this object I employ a pair of cylinders rotating continuously and each with the same peripheral speed as the other, said cylinders being equipped with printing plates and one or more impression plates so disposed around said cylinders that a printing plate and an impression plate will be in opposition at determinate points in the rotation of said cylinders. A portion of the web is carried forward through the printing point while said surfaces are in opposition, said portion of the web being then moved backward to position for another impression at the same point in the length of the web, while the next printing surface in the series is rotating to position for another impression. I also employ, in combination with the foregoing, intermittently-operating web-feeding means adapted to carry into the machine at each operation the exact length of web required and simultaneously to draw from the machine an exactly equal length of the same. I also employ in my printing machine a novel form of web-cutting device for severing the printed sheet from the web.

In the drawings accompanying this specification, Figure 1 is a broken elevational side view of a printing machine constructed in accordance with my invention. Fig. 2 is a reversed vertical longitudinal sectional view of the same on a slightly enlarged scale; some of the parts being omitted. Fig. 3 is an elevational side view of a portion of the machine showing the side opposite

that shown in Fig. 1. Fig. 3^a shows in elevation a box cam adapted to actuate the sheet-severing mechanism. Fig. 4 is an enlarged detail showing the inking devices for one of the cylinders. Fig. 5 is a view similar to Fig. 4, but looking at the other side of the machine, 60 and showing in detail the means for throwing the inking devices into and out of contact with their corresponding printing surfaces. Fig. 6 is an enlarged elevational side view of a portion of the machine, showing the intermittently-operating web-feed and discharge mechanism. Fig. 7 shows the same in vertical cross-section. Fig. 8 is a detail of certain parts of the same. Fig. 8^a is a plan view of the dog or pawl shown in Fig. 8. Fig. 9 is a vertical sectional view of the web-cutting device which severs the printed sheet from the end of the web. 70 Figs. 10 and 11 are respectively an elevation and a cross-sectional view of the oscillating member of the cutting-off device shown in Fig. 9.

In the several figures of the drawings, 1 is the frame of the machine, 2 is the main shaft having upon one of its ends the fly-wheel 3 and the driving pulley 4.

Keyed upon the opposite end of the main shaft 2 is a pinion 5 meshing with a gear 6. This gear 6 is secured upon the shaft 7 of a printing cylinder 8 and meshes with a similar gear 9, secured to the shaft 10 of another printing cylinder 11. The printing cylinders 8 and 11 are thus made to rotate synchronously and with the same peripheral speed. The peripheries of one or both of these cylinders 8 and 11 are divided into a number of substantially equal parts, alternate parts 85 being recessed, as best shown in Fig. 2, and so disposed around the cylinders that, when said cylinders are rotating, a high portion on one cylinder will always meet a corresponding high portion on the other cylinder and, conversely, a recessed or low portion on one of the cylinders will meet a low portion on the other cylinder. The high portions of the cylinders are adapted, in a familiar manner, for the attachment thereto of curved plates. These plates may be either smooth impression plates or printing plates such as electrotype or stereotype plates, as desired.

The web is drawn from the roll 12 and passes under the roller 13, thence upwardly and over the roller 14 and between this latter and the superimposed roller 15. From this point it passes to the roller 16 and is led therefrom to a roller 17, thence downward and under a roller 18. This roller 18 is carried by a vertically-movable gate and has movement therewith. The gate consists of a pair of rods 19 and 19^a, moving in slide bearings 20 and 20^a near their lower ends and in slide bearings 21 and 21^a near their upper ends. Carried by the gate adjacent the upper ends of the rods 19 and 19^a is a roller 22. This latter roller is vertically adjustable upon the gate, whereby the distance between the rollers 18 and 22 may be varied for a purpose hereinafter explained. Carried 110

by the rods 19 and 19^a are cam-rollers 19^b and 19^c, these rollers riding upon the peripheries of a pair of open cams 25 and 25^a which are mounted upon opposite ends of the shaft 26, the latter being driven by the gear 27^a which meshes with the gear 28 upon the shaft 26, and with the pinion 5 on the main shaft 2 of the machine.

From the roller 18 the web passes upward to and over the roller 22, thence downward and under a stationary roller 23 and is led from this roller to the roller 24, passing below the same and between it and the roller 15.

The rollers 14, 15 and 24 are geared together so as to rotate with the same peripheral speed. It will be seen that by this means the length of paper drawn into the machine by the rotation of these rollers is exactly equal to the length of web discharged from the machine by the rotation of such rollers. Means are provided whereby these rollers 14, 15 and 24 have imparted to them an intermittent rotation, this movement occurring at the proper period in the cycle of operations of the machine.

The means whereby this is accomplished will be explained hereinafter.

The operation of the machine in drawing the web from the roll, printing upon the same a number of times at the same point in its length, discharging the same from the machine and cutting it into sheets is as follows:—The cylinders 8 and 11 rotate continuously and in the direction indicated by the arrows in Figs. 2 and 3. If it be desired to print twice at the same point on the same side of the web in two colors, the high portions 30 of the cylinder 8 will be equipped with printing plates, and the corresponding high portions of the cylinder 11 will be equipped with impression plates with the usual tympan sheets stretched upon the same. The gate carrying the rollers 18 and 22 is lifted by the pair of open cams 25 and 25^a, as hereinbefore explained, and carries with it through the printing point between the cylinders the portion of the web supported by said gate. These cams 25 and 25^a are so formed and their movement is so timed with relation to the rotation of the cylinders 8 and 11, that the gate rises continuously while the plate-bearing portions of those cylinders are in opposition, and a printing operation is occurring, and is lowered during the interval between two successive printing operations when the recessed portions of the cylinders 8 and 11 are in opposition. The rollers 14, 15 and 24 are at rest during the upward movement of the gate and the amount of paper within the machine, therefore, is unchanged during this movement and while a printing operation is taking place. The cams 25 and 25^a 45 are formed so as to lift the gate with the proper speed to move the portion of the web supported by such gate through the printing point between the cylinders at the exact speed of the printing and impression surfaces, whereby a printed impression is properly placed upon the web. These cams are arranged to also lower the gate and thereby to carry back the portion of the web already printed upon and preferably at a much more rapid rate than that at which it is carried up, and while the rollers 14, 15 and 24 remain at rest. If it be desired 50 to use the machine as a perfecting press, printing upon both sides of the paper, each cylinder will have placed thereupon a printing plate and an impression plate, these plates being so arranged that each printing plate will be met by a corresponding impression plate as it 60 rotates toward the printing point. The action of the 65

web-lifting gate will be the same in this case as in the case where the two impressions are placed upon the same side of the paper, as above described.

It will be seen that if the cylinders 8 and 11 are formed with two high portions and two low portions, as shown herein, and with the gate adapted to lift and return the web twice during each complete revolution of these cylinders, two impressions will be placed upon the web at exactly the same point in the length of the web so that exact registration can be insured either upon the same side or upon opposite sides thereof. If desired these cylinders may be peripherally divided into six or more portions, a high portion alternating with a low portion. The gearing by which the shaft 26, upon which are mounted the cams 25 and 25^a, is driven, 80 would then be arranged so that the cams would rotate and lift the gate as many times during the rotation of the cylinders 8 and 11 as there were printing plates upon the cylinder. During the running of the machine the cylinders 8 and 11 rotate continuously and the web-carrying gate reciprocates vertically and continuously, the latter moving upward while the complementary high surfaces upon the two cylinders are in opposition, and descending after these high surfaces have passed out of opposition, and while the next following pair of complementary high surfaces are rotating to printing position.

If no new length of paper were fed into the machine an indefinite number of impressions would be placed upon the web at the same point. The paper is therefore given a forward movement after the desired number of registering impressions, in this case two, have been placed thereupon. This result is accomplished by suitable means adapted to throw the intermittently-actuated feed and discharge rollers 14, 15 and 24, into operation after each series of registering impressions has been made, or, when constructed as here shown, after the cylinders have made a complete revolution. In some cases it is desirable that these feed and discharge rollers be actuated after each impression. This 105 will be the case when two identical printing plates are employed, in which case it would not, of course, be desired to superimpose the printed impression obtained from one of these plates upon that obtained from the other plate. With such an arrangement of plates 110 the feed and discharge roller actuating means are set to give a forward impulse to the web after each printing operation. There is thus given to the machine a double capacity for single-impression work.

In Figs. 6 and 7 are shown the means for operating 115 the feed and discharge rollers and the means for changing from single-impression to double-impression feed, and vice versa. Upon the shaft 28 of the roller 15 is loosely mounted a gear 29, this gear being rotated back and forth by the sector gear 30, the latter being 120 oscillated by the pitman 31 which is secured at one of its ends to the sector gear 30, and at its opposite end to a variable crank 32 upon the shaft 33. This shaft is driven by the gear 34, which is keyed thereupon, and meshes with the gear 9. (See Fig. 3.) The variable 125 crank 32 provides means whereby the length of the throw of the sector gear 30, and consequently the length of web drawn into the machine at each operation of the feed device, are regulated. Connected to the loose gear 29 and rotating therewith, is a dog-carrying disk 130

35, having a boss 36 to which is pivoted a dog or pawl 37. (Figs. 7 and 8). This dog is adapted to engage teeth upon a ratchet disk 38, which is fast upon the shaft 28. As the sector gear 30 oscillates, the gear 29 5 is rotated back and forth, the dog-carrying disk 35 being carried therewith, and the dog 37 engaging the teeth on the ratchet disk 38 to drive it in one direction, but riding over these teeth when moving in the other direction. In this way the shaft 28, and the 10 roller 15 upon this shaft, are given an intermittent movement in one direction. As the rollers 14 and 24 are connected by gearing with the roller 15, opposite, so as to rotate with the same peripheral speed, the web, which enters the machine between the rollers 14 and 15 and leaves the same between the rollers 15 and 24, will be drawn into the machine and from the machine with exactly the same speed, the amount of paper 15 within the machine being maintained constant at all times.

20 The ratchet disk 38 is formed with a hub 39 loosely mounted upon which is an idler disk 40. The dog 37 is provided with a tongue 41 adapted to rest in a notch 42 in the edge of the idler disk 40. The idler disk is thus loosely connected with the pawl-carrying 25 disk 35 and is thrown back and forth thereby. The office of this idler disk is to serve, by its inertia and momentum, to lift and lower the dog or pawl 37 out of and into engagement with the teeth of the ratchet disk 38 at the proper time. It will be seen that when the 30 point 37, of the dog 37, is inserted between the teeth on the ratchet disk 38, and the latter is given a thrust by the rotation of the sector gear 30, the ratchet disk 38 and the shaft 28 upon which this disk is secured, will be rotated and the rollers 14, 15 and 24 will turn 35 and draw into the press, and at the same time discharge therefrom, a certain length of the web. When this movement of the disk and rollers is suddenly arrested, by reason of the sector gear 30 reaching the limit of its movement and starting back in the opposite direction, 40 the idler disk 40, by its momentum, will tend to continue in rotation and will lift the point of the pawl or dog 37 out of engagement with the teeth of the ratchet disk 38. When the pawl-carrying disk 35 is rotated in the opposite direction by the movement of the sector 45 gear 30 on its return thrust, the idler disk 40 will be moved backward therewith. When the pawl-carrying disk 36 and sector gear 30 have reached the limit of their movement in the backward direction the idler disk 40, by its tendency to continue in motion, will 50 throw the point of the dog or pawl 37 down against the teeth of the ratchet disk 38. Upon the next forward movement of the sector gear 30 and pawl-carrying disk 35 the ratchet disk 38 will, of course, be carried forward. The ratchet disk 38, shaft 28 and rollers 14, 55 15 and 24 are thus given an intermittent movement in the direction to carry the paper into the machine between the rollers 14 and 15, and to draw the same from the machine between the rollers 15 and 24.

In some cases it is desirable that the web be moved 60 forward by the rollers 14, 15 and 24 after each printing operation, or, in other words, twice during a complete revolution of the cylinders 8 and 11. This would be the case when, as hereinabove pointed out, it was not desired to print twice at the same point in 65 the length of the web, either upon one side of the same

in different colors or upon opposite sides thereof. As shown the gear 34 keyed to the shaft 33, is adapted to revolve twice to each revolution of the gear 9 with which it meshes, and as the latter revolves with one of the cylinders, it is evident that the variable crank 70 32, carried by the shaft 33, will actuate the pitman 31 and sector gear 30, twice during each revolution of the cylinders. The rollers 14, 15 and 24 are thus made to pull the web along after each printing operation. When, however, as is more often the case, it is desired 75 to print twice upon the web at the same point in its length the means that are adapted to be set so as to cause the rollers 14, 15 and 24 to move forward after alternate printing operations, or, in other words, once to each rotation of the cylinders, may be described as 80 follows: The star wheel 43, (Figs. 1 and 6), is adapted to be struck and moved forward a distance, equal to that between two of its points, at each movement in one direction of the sector gear 30 by a pawl 44, carried by said sector gear 30. Upon one side of the 85 star wheel 43 is a face cam 45 rotating therewith. This face cam 45 is formed with a wave-line face, and a roller 46 is adapted to ride upon this face (Fig. 7). The roller 46 is carried by a sliding, outwardly-spring-pressed rod 47. This rod 47 carries a disk 48 which 90 is adapted to be moved toward and away from the ratchet disk 38 by the reciprocation of the rod 47 within its bearings. The depressions and elevations upon the face of the cam 45 are so spaced around the latter that alternate movements given thereto by the 95 contact of the pawl 44 with the points of the star wheel 43, will move the rod 47 and disk 48 away from the ratchet disk 38 against the thrust of the spring 49, the disk 48 being returned to engagement with the disk 38 during the interval while the pawl 37 is held 100 up by the idler disk 40. Whenever the disk 48 has come into contact with the side of the ratchet disk 38, the point of the pawl 37, which is somewhat wider than the thickness of the ratchet disk 38, will ride upon the edge of the disk 48, the diameter of which 105 is equal to, or greater than, that of the line of the points of the teeth of the ratchet disk 38. The ratchet 37 is thus intermittently prevented from dropping into the notches between the teeth of the ratchet disk 38. It will be seen that by this means the ratchet 110 disk 38, shaft 28 and rollers 14, 15 and 24, are thus caused to rotate after each alternate forward movement of the sector gear 30, and as this sector gear, as above pointed out, is given a forward thrust twice during each revolution of the printing cylinders, the 115 web will be moved by these rollers once only during each revolution of the cylinders, when this part of the machine is in operation. When it is desired to set the machine so that it will move the paper forward after each printing operation, or twice during a revolution of the cylinders, the pawl 44 will simply be loosened and moved around on its pivot into such a position that it will not engage the teeth on the star 120 wheel 43.

The web, after passing out between the rollers 15 125 and 24, goes to the sheet-severing device, (Fig. 9), which comprises an oscillating blade 50, a stationary blade 51, and means for oscillating the movable blade 50 past the edge of the stationary blade during the interval between the forward movements of the web. 130

The blade 50 is secured to the lower side of a substantially semi-cylindrical oscillating member 52. This member 52 is provided with extended ends 53 and 53^a forming trunnions, adapted to rest in suitable bearings on the frame of the machine. The flat side of the oscillating member 52 is given a slight longitudinal incline or dip instead of being parallel to the axis of rotation of said member. The axis of rotation of the member 52 is a line passing through the centers of the trunnions 53 and 53^a. The bearings in which these trunnions are supported are in line with each other and parallel to the upper edge of the blade 51. The result of this arrangement of the parts being that one end of the blade 50 will pass the edge of the vertical blade 51 slightly ahead of its opposite end.

Projecting downwardly from the trunnion 53 and secured thereto is a crank 55 having a pivotal connection with one end of a connecting-rod 56. The opposite end of this connecting-rod 56 is provided with a cam-following roller 57, adapted to travel in the groove of a box-cam 58. (Fig. 3.) The box-cam 58 is carried by the gear 9 and revolves once to each revolution of the cylinders 8 and 11. There is thus given to the sheet-severing device a movement after each alternate printing operation, or, by the substitution for the cam 58 of the two-throw cam 58^a shown in Fig. 3^a, this sheet-severing device may be made to operate after each printing operation. This latter method is sometimes employed when single-impression work is being executed. The blade 51 is preferably made slightly flexible so that it will always bear with a slight yielding pressure against the edge of the oscillating plate 50 whereby a clean sharp cut is assured. Adjustment of the movable blade 50 toward and away from the stationary blade 51 is made by loosening the screws 54^a. These screws pass through slots in the bracket 52^a, which carries the bearings for the trunnions 53 and 53^a. By turning the screw 50^a in or out the bracket and knife carried thereby are moved toward or away from the stationary knife, the screws 54^a being tightened again after the proper adjustment has been secured.

Each of the inking devices with which the machine is provided is adapted to ink its own plate and to have its plate-inking rollers moved away from the line of the printing surfaces of the various plates at the proper period in the rotation of the cylinders 8 and 11, to cause these plate-inking rollers to miss the plates which they are not designed to ink. In each of these inking devices 59 designates an ink fountain of the usual form, having a fountain roller 60 forming one of its sides, and the inclined plate 61 forming the bottom of said fountain and in contact with the bottom of the roller 60.

The roller 60 is given a step by step movement by the following described mechanism: On the shaft of the roller 60 is secured a ratchet wheel 62, (Fig. 4), engaged by a pawl 63, mounted on the pawl-carrier 64, the latter oscillating with the arm 65, one end of which is pivoted to the outer end of the link 66, the opposite end of the link 66 being pivoted to the side of the gear 6, at a point slightly removed from the center of rotation of the same. As the gear 6 rotates the link 66 and arm 65, by their movement, cause the pawl-carrier 64 to oscillate back and forth, the pawl 63 carried thereby engaging the teeth on the ratchet disk 62 when said

pawl-carrier moves in one direction, and riding over said teeth when the ratchet is moving in the opposite direction, the roller 60 thus being given a step by step movement in one direction and the ink being drawn from the fountain by this movement in the usual manner. A ductor roller 67 is oscillated back and forth between the roller 60 and a steel distributing roller 68, alternately taking ink from the fountain roller 60 and placing it upon the distributing roller 68. This is accomplished by the movement of a cam-roller 69^a running in a box-cam 69 upon the end of the cylinder 7 opposite that to which is secured the gear 6. This cam-roller 69^a is carried upon one end of a lever 70, the latter being pivoted intermediate its ends, and having pivoted to the outer end thereof, a link 71. The outer end of the link 71 is connected with a lever 72, the latter being mounted upon the end of a rock-shaft 73.

Secured to the shaft 73 near each of its ends, is a bell-crank lever 74. These levers 74 have bearings for the ductor roller 67. The oscillation of the lever 70, by the movement of the cam roller 69^a in the groove of the cam 69, is transmitted through the link 71, lever 72, rock-shaft 73 and lever 74, to the ductor roller 67 causing the latter to oscillate between the fountain roller 60 and the distributing roller 68. The distributing roller 68 is constantly revolved by a gear 68^a upon the shaft of this roller and a pinion 68^b between the gear 68^a and the gear 6.

Rotating in contact with the roller 68 are the plate-inking or form rollers 75 and 76. These rollers are adapted to remain in contact with the distributing roller 68 at all times, but to move around said distributing roller toward or away from each other and into and out of engagement with the printing surfaces upon the cylinders. A suitable boss 77 is arranged at each side of the machine and forms a part of the frame. These bosses form bearings for the roller 68 and are also each adapted to provide bearings or fulcrums for a pair of levers 78 and 79. These levers, pivoted upon the bosses 77, cross each other. A link 80 connects the outer end of the lever 78 with a bell-crank lever 81, the latter being secured on the shaft 73. The opposite end of the lever 78 carries the form-roller 76. Similarly, the outer end of the lever 79 is connected by the link 82 with a bell-crank lever 83, the latter being fast on the shaft 73 and the form-roller 75 is carried by the inner end of the lever 79. Oscillating motion is transmitted from the cam-roller 69^a, running in the groove of the cam 69, through the lever 70, link 71 and lever 72, to the shaft 73. From this point motion is imparted through the bell-cranks 81 and 83, links 74 and 82, to the levers 78 and 79. The rollers 75 and 76 carried by these levers 78 and 79 are, therefore, given a movement toward and away from the plate-carrying cylinder simultaneously. The cam-rollers 69^a are so disposed in the groove of the cam 69 as to receive movement and to impart the same to the movable rollers of the inking devices at the proper time, so that each plate will be inked by its own set of inking rollers, and these rollers will miss the plate upon the opposite side of the cylinder.

It is necessary to vary the point at which the web is cut between two printed impressions whereby the impression may be "located" upon the printed sheet resulting from the operation of the machine. This result is accomplished by a simple method which con-

sists in varying the length of that portion of the web which is between the printing point of the press and the sheet-severing device. A simple and convenient method of so varying the length of this portion of the 5 web is shown herein and consists in making the upper roller 22, upon the web-carrying gate, vertically adjustable upon the posts of said gate. To this end I form the upper ends of the posts 19 and 19' with a series of rack-teeth which are engaged by the teeth of a pinion 84, this pinion being rotated by a hand-wheel 85, so as to move the bracket 86, which carries the roller 22, pinion 84 and hand-wheel 85, up or down on the post. A set screw 87, adapted to be tightened against the post, prevents the movement of the bracket 86 along the post 15 after the same has been adjusted to proper position.

I claim:

1. In a web-printing machine, the combination of intermittently operating means for drawing the web into said machine, and continuously-rotating, printing means adapted to intermittently print upon the web, said first-named means being also adapted to draw the web from the machine and arranged to operate during the interval between printing operations.
2. In a web-printing machine, the combination of continuously-rotating, printing means adapted to intermittently print upon the web, and means for intermittently feeding the web to the machine, said means being arranged to operate between two successive printing operations, and adapted also to draw the web from the machine, 30 said last-named operation occurring simultaneously with said web-feeding operation.
3. In a web-printing machine, the combination of a web-feeding device adapted to intermittently feed the web to the machine, means for varying the length of web fed to said machine by each operation of said feeding means, said feeding means being arranged to simultaneously withdraw a length of web equal to the length fed to the machine, and rotary, printing means adapted to act upon said web intermediate said web-feeding and withdrawing 40 means between successive operations of said web-feeding device.
4. In a rotary printing machine, the combination with means for intermittently feeding the web into the machine, of means for simultaneously withdrawing an equal length 45 of the web, and means for supporting a portion of the web and adapted to move such portion through the printing point of said printing machine and to return said portion to position for a second impression while said feed and withdrawing devices are idle.
5. In a rotary web-printing machine, the combination of a continuously-rotating segmental impression surface, a continuously-rotating segmental printing surface, said printing and impression surfaces timed to oppose each other at regular intervals, means adapted to feed a pre-determined length of the web into the machine while said impression and printing surfaces are out of opposition with each other, and at the same time to draw from the press an equal length of the web, and means adapted, while said segmental surfaces are in opposition, to draw a 55 portion of said web between said surfaces for the reception thereon of the printed impression and to return the same for another impression while said impression and printing surfaces are out of opposition.
6. In a web-printing machine, the combination of a plurality of rotary printing surfaces, a rotary impression surface, means adapted to carry a portion of the web through the printing point when one of the printing surfaces is opposed to an impression surface and to return said portion of the web for another impression while said printing surface is out of opposition with the impression surface, said means being adjustable to vary the distance between the printing point and the discharge device whereby the impression may be located upon the printed sheet resulting from the operation of the machine.
7. In a web-printing machine, the combination of a plurality of rotary printing surfaces, a rotary impression sur-

face, means adapted to carry a portion of the web through the printing point when one of the printing surfaces is opposed to an impression surface and to return said portion of the web for another impression while said printing surface is out of opposition with the impression surface, means adapted to cross-cut the web and means to adjustably vary the length of the portion of the web between the printing point and said cut-off means; whereby the printed impression may be located upon the printed sheet resulting from the operation of the machine.

8. In a web-printing machine, a plurality of rotating printing surfaces, a rotating impression surface, an intermittently operating feeding device for said machine adapted to feed a determinate length of web into said machine, an intermittently operating discharge device adapted to operate simultaneously with said feed device and to draw from the machine the same length of web, the rotating printing surfaces adapted to engage the web while the feed and discharge devices are inoperative, and suitable means for moving a portion of said web through the printing point while one of said printing surfaces is in contact with the web.

9. In a web-printing machine, rotating printing surfaces adapted to engage the web at regular intervals, means carrying a portion of said web and adapted to move same through the printing point during each printing operation and adapted to be set so as to return said portion of the web for another impression a predetermined number of times whereby successive impressions may be placed upon the web at the same point in the length thereof.

10. In a rotary web-printing machine, the combination of a cylinder carrying a segmental printing surface a cylinder carrying a segmental impression surface, said cylinders rotating continuously and with the same peripheral speed, said printing and impression surfaces so disposed upon the cylinders as to oppose each other at regular intervals, means adapted to carry a portion of the web through the printing point at a speed equal to the peripheral speed of the printing surfaces while the impression surface and printing surface are in opposition, whereby said web receives an impression, and means adapted, when said impression and printing surfaces are not in opposition, to move said portion of the web back to position for a second impression at the same point in the length of the web.

11. In a rotary web-printing machine, the combination of a plurality of rotating impression surfaces, a plurality of rotating printing surfaces, said impression and printing surfaces timed to automatically oppose each other at regular intervals, and a web-feeding device adapted to be inoperative while a printing surface and an impression surface are in opposition with each other and to feed a predetermined length of the web into the machine during the interval between two successive printing operations.

12. In a rotary web-printing machine, a pair of cylinders adapted to rotate with the same peripheral speed, each of said cylinders being provided with a plurality of plate-carrying surfaces adapted for the interchangeable attachment thereto of printing or impression surfaces, and means adapted to carry a portion of the web through the printing point while a printing surface upon one of said cylinders and an impression surface upon the other of said cylinders are in opposition and to return said portion while said surfaces are out of opposition for a second impression at the same point in the length of the web.

13. In a rotary web-printing machine, the combination of continuously-rotating cylinders each having a plurality of surfaces adapted for the interchangeable attachment thereto of printing or impression plates, and so disposed around the cylinders that one of said surfaces upon each of the cylinders will be in mutual opposition at regular intervals, means adapted to carry a portion of the web through the printing point while said surfaces are in opposition and to return to its original position while said surfaces are out of opposition, and means adapted to draw from the machine a predetermined length of the web, said last-named means being adjustable so as to permit the same to operate either after each operation of said first-named means or after alternate operation of said first-named means as desired.

14. In a rotary web-printing machine, the combination of a pair of cylinders, each of said cylinders provided with a plurality of surfaces adapted for the attachment thereto of plates, means adapted to support a portion of the web and having vertical movement, said means arranged to move the web upward through the printing point while said surfaces are in opposition and to move downward while said surfaces are out of opposition, and means for drawing from the machine a predetermined length of the web while said carrying means is descending, said last-named means being adjustable at will so as to operate either upon every downward movement of said carrying means or upon every alternate downward movement of the same.
15. In a rotary web-printing machine, the combination of means for feeding a predetermined length of the web into said machine and simultaneously drawing from said machine an equal length of the web, and rotary printing means adapted to automatically act upon said web at a point intermediate the ends of the portion of said web within the machine while said feed and discharge devices are inoperative.
16. In a rotary web-printing machine, the combination with a pair of continuously-rotating cylinders, of a plurality of printing plates carried by said cylinders, an impression surface adapted to oppose each of said printing plates, a plurality of inking devices, means for causing each of said printing devices to ink one only of said plates, and means adapted to support a portion of the length of the web and adapted to carry said portion through the printing point while one of said printing plates is in opposition to an impression surface, said means adapted to return said portion of the web to position for the reception thereon of another impression a predetermined number of times whereby successive impressions in different colors may be made upon said web at the same point.
17. In a rotary web-printing machine, the combination of a plurality of rotating printing plates, an impression surface adapted to oppose each of said plates, said members being so arranged that all of said printing plates have a common printing point, means adapted to support a portion of the length of the web, said means adapted to carry said portion through said printing point a desired number of times, and a separate inking device for each of said plates adapted to ink its corresponding plate whereby a plurality of printed impressions may be made upon the web at the same point in the length thereof.
18. In a web-printing machine, the combination of a cylinder carrying a plurality of segmental printing surfaces, a cylinder carrying an impression surface, said cylinders rotating continuously and with the same peripheral speed, said impression surface and printing surfaces so disposed upon the cylinders as to oppose each other at regular intervals, means adapted to carry a portion of the web through the printing point at a speed equal to the peripheral speed of the printing surfaces while an impression surface and a printing surface are in opposition, whereby said web receives an impression, and means adapted, when said impression and printing surfaces are not in opposition, to move said portion of the web back to position for a second impression at the same point in the length of the web.
19. In a web-printing machine, a combined feed and discharge mechanism comprising an intermittently rotated roller, a second roller rotating with the same peripheral speed as said first-named roller and in contact therewith, the web entering the machine between said first-named roller and said second-named roller, and a third roller contacting with said first-named roller and also rotating with the same peripheral speed as the first-named roller, the paper being discharged from the machine between said first-named roller and third-named roller, and means adapted to print upon said web during an interval between movements of the intermittently rotated roller.
20. In a printing machine, combined feed and take-off mechanism comprising an intermittently rotating roller, a second roller rotating in contact with said first-named roller and with the same peripheral speed, the paper web being drawn into the machine between said first-named and second-named rollers, and a third roller also
- rotating in contact with said first-named roller and at the same peripheral speed, the web being drawn from the machine between said first-named and third-named rollers and discharged from the machine thereby, combined with a plurality of printing surfaces, and means for causing all of said printing surfaces to print successively upon the web at the same part of its length during an interval between movements of said rollers.
21. In a web-printing machine, the combination of three intermittently rotating rollers arranged in tandem and 90 rotating with the same peripheral speed, the web entering the machine between two of said rollers and leaving the machine between two of said rollers, and a rotating cylinder carrying a plurality of printing surfaces adapted to successively print upon the web at the same part of its 95 length, said rollers and printing means being constructed to operate alternately.
22. In a web-printing machine, the combination of a plurality of rotating printing surfaces adapted to engage the web at regular intervals, a pair of rollers, one of said 100 rollers being at each side of the printing point, said rollers being parallel and moving simultaneously to carry a portion of the web through the printing point during a printing operation and to return the same for another impression between two consecutive printing operations, a web-cutting device at the discharge end of the machine, and means for adjustably varying the distance between said rollers, whereby the length of that portion of the web which is between the printing point and the cutting device may be varied so as to locate the point at which the web 105 is cut between two adjacent impressions.
23. In a rotary web printing machine, the combination of a rotating cylinder carrying a plurality of printing surfaces, means for carrying a portion of the web past said cylinder a plural number of times, so that successive 110 impressions are printed upon the same portion of the web, and an independent inking device for each of said printing surfaces, each of said inking devices comprising a pair of crossed levers pivoted at their crossing point, each of said levers bearing a form-roller, the opposite end of each of said levers having connected therewith a link, a rock-shaft, a pair of levers secured to said rock-shaft and having each an end connected with one of said links, and means for oscillating said rock-shaft.
24. In a rotary web printing machine, the combination 115 of a rotating cylinder bearing a plurality of printing surfaces, means for carrying a portion of the web through the printing point of the machine a plural number of times, so that successive impressions may be printed upon the same part of said web, a cam rotating with said 120 cylinder, a cam follower corresponding to each of said printing surfaces and adapted to engage said cam, a rock-shaft corresponding to each of said cam followers and adapted to be rocked by the movement of the same, and one or more form-rollers connected with each of said 125 rock-shafts and adapted to be moved toward and away from the printing surfaces by movement of the said rock-shaft, each of said cam followers being so located as to cause its corresponding form-rollers to engage one only of said printing surfaces and to miss the others of said 130 printing surfaces.
25. In a rotary web printing machine, the combination of a rotating cylinder bearing a plurality of printing surfaces, a web-carrying device constructed to carry a portion of the web through the printing point of the machine 145 a plural number of times and thereby to cause said printing surfaces to successively engage the web at the same part of its length, a rock-shaft corresponding to each of said printing surfaces, one or more form-rollers connected with each of said rock-shafts and means rotating with 150 said cylinder and adapted to impart to each of said rock-shafts movement at the proper time to cause each of the form-rollers to ink one only of said printing surfaces and to miss the other of said printing surfaces.
26. In a rotary web printing machine, the combination 155 of a rotating cylinder bearing a plurality of printing surfaces, said printing surfaces being adapted to print successive impressions upon the same part of the web, a cam rotating with said cylinder, a cam follower corresponding to each of said printing surfaces, a plurality of rock-

- shafts each rocked by the movement of one of said cam followers, levers carried by each of said rock-shafts, a roller having bearings in said levers, a fountain roller upon one side of said first-named roller, a distributing roller upon the opposite side of said first-named roller, said first-named roller being adapted to be oscillated between said last-named rollers by the movement of the rock-shaft.
27. In a web printing machine, means for carrying into the machine a predetermined length of web and means for simultaneously drawing from the machine an equal length of web, means for printing successive impressions upon the same part of said web between the feed and take-off devices, said printing means being adapted to work alternately with the feed and take-off devices, and sheet-severing device, comprising the combination of a stationary blade, an oscillating member having its axis of oscillation parallel with the cutting edge of said stationary blade, and a blade carried by said oscillating member, said blade being arranged upon said oscillating member with its cutting edge inclined to the axis of oscillation of said oscillating member and arranged to pass the edge of the stationary blade in cutting engagement therewith.
28. In a web printing machine, printing means adapted to print a plurality of successive impressions upon the same part of the web, intermittently operating means for feeding the web into and out of the machine, said printing means operating during an interval between two successive operations of the sheet-feeding device, and a sheet severing device therefor constructed to operate during the interval between two successive movements of the web from the machine, said sheet-severing device comprising in combination a stationary blade having a cutting edge and an oscillating blade arranged with its axis of oscillation parallel with the cutting edge of said stationary blade and having a cutting edge inclined to said axis of oscillation and adapted to engage the cutting edge of said stationary blade.
29. In a web printing machine, means adapted to feed into the machine a predetermined length of web and at the same time to draw from the machine an equal length of web, means for printing successive impressions upon the same part of the web, said web-feeding and web-discharge devices being idle during the operation of the printing means, and a sheet severing device, comprising a flexible fixed blade having a cutting edge parallel with the plane of the web, an oscillating blade having a cutting edge adapted to pass the edge of the fixed blade in cutting engagement therewith, said oscillating blade having its cutting edge inclined to the cutting edge of the fixed blade.
30. In a web printing machine, wherein the web is intermittently advanced, means for printing successive im-
- pressions upon the same part of said web during the interval between successive forward movements of the web, and a sheet severing device therefor, also adapted to operate during an interval between successive forward movements of the web, said sheet-severing device comprising in combination a fixed blade having its cutting edge parallel with the plane of the web, a movable blade having a cutting edge inclined to the cutting edge of the fixed blade and adapted to pass said edge in cutting engagement therewith and means for imparting movement to said movable blade during an interval between two successive forward movements of the web.
31. In a rotary web printing machine, a cylinder, a plurality of segmental printing surfaces carried by said cylinder, means whereby all of said segmental printing surfaces are caused to print upon the web at the same part of the length thereof, and means for intermittently advancing said web, comprising a roller with which said web engages, a ratchet disk rotating with said roller, an oscillating pawl carrier, a pawl carried thereby and adapted to engage teeth upon said ratchet disk when moving in one direction, an idler disk loosely connected with said pawl and adapted by its inertia and momentum to lift and lower said pawl, and means adapted to be inserted beneath the point of said pawl while the latter is in its raised position and upon which the point of said pawl may ride without engaging the teeth of the ratchet disk, and means adapted to move said last-named means toward and away from the ratchet disk at determinate intervals.
32. In a web printing machine, the combination of continuously rotating printing means adapted to intermittently print upon the web, and means for intermittently feeding the web through the machine, said means being arranged to operate between successive printing operations and comprising a roller adapted to be engaged by the web upon each side of said roller and to advance the web into the machine by its engagement with said roller upon one side and to draw from the machine an equal length of the web by its engagement with the opposite side of said roller and means for intermittently rotating said roller, said means comprising a ratchet disk rotating with said roller, an oscillating pawl carrier, a pawl carried thereby and adapted to engage teeth upon the ratchet disk when moving in one direction, a pinion oscillating with said pawl carrier, a sector-gear meshing with said pinion, a variable crank constantly rotating and a pitman connecting said crank and said sector-gear.
